CLAIM

The ornamental design for a hummingbird feeder, as shown and described.

DESCRIPTION

FIG. 1 is a top, front perspective view of a hummingbird feeder, showing my new design;

FIG. 2 is a bottom, rear perspective view of the hummingbird feeder;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dot-dash broken line in FIGS. 1 and 7 defines the bounds of the claim and forms no part thereof.

1 Claim, 8 Drawing Sheets
